CLAIM

The ornamental design for a display screen or portion thereof with graphical user interface substantially as shown and described.

DESCRIPTION

The file of this patent contains at least one drawing/photograph executed in color. Copies of this patent with color drawing(s)/photograph(s) will be provided by the Office upon request.

The sole FIGURE is a front view of a display screen or portion thereof with a graphical user interface showing the claimed design.

The broken lines in the FIGURE show a display screen or portion thereof, and form no part of the claimed design.
